UNITED STATES PATENT OFFICE.

CHARLES SUMNER WARREN, OF TORONTO, ONTARIO, CANADA.

STOP-ACTION FOR REED-ORGANS.

SPECIFICATION forming part of Letters Patent No. 425,156, dated April 8, 1890.

Application filed February 23, 1889. Renewed February 13, 1890. Serial No. 340,274. (No model.)

To all whom it may concern:

Be it known that I, CHARLES SUMNER WARREN, of the city of Toronto, in the county of York and Province of Ontario, Canada, have 5 invented certain new and useful Improvements in Stop-Actions for Reed-Organs; and I do hereby declare that the following is a full, clear, and exact description of the same.

This invention relates to the stop-actions of 10 reed-organs of one or more manuals, and is more especially designed for use in connection with that superior class where there are end wind-trunks and a series of wind-chests and different rows of reeds arranged one 15 above the other, as in my former application filed March 22, 1888, Serial No. 268,163.

My improvements have for their object to adapt a pneumatic stop-action to this class of instruments—that is to say, where the organ 20 is of the "pressure" class in contradistinction to "suction" organs.

By the special features of construction, novel elements, and combinations of parts embodied in this invention I obviate all the 25 difficulties and objections heretofore experienced in operating slides, hinged flaps, and such like devices in reed-organs of this kind for controlling the wind between the main wind-trunk and the several wind-chests and 30 reed-chambers, and produce a stop-action at once noiseless, positive, and easy and efficient in operation.

For full comprehension of the invention and of the several features of construction, 35 reference must be had to the accompanying drawings, forming part of this specification, in which similar letters of reference indicate like parts.

In said drawings, Figure 1 is a plan view 40 illustrating several stops and levers in connection therewith for operating the pneumatic valves. Fig. 2 is a vertical sectional elevation (looking at the rear of Fig. 1) showing said levers in connection with said valves, the valve-chest, main wind-trunk, wind-chests, 45 and my devices for controlling the wind between the same. Fig. 3 is a face view (on reduced scale) of the wind-trunk, showing arrangement of air-pipes between valve-chest 50 and pallets covering openings to the several wind-chests. Figs. 4, 5, and 6 are respectively a plan, horizontal section, and end view

of the pallet in its relation to the wind-chest. Fig. 7 is a bottom plan of the valve-chest and valves. Fig. 8 is a top plan of the same, the 55 casing being in section. Figs. 9 and 10 are horizontal sectional elevations illustrating a stop-lever, the valve it controls, and the valve-chest, the same showing the valve in its open and closed positions, respectively. 60

A represents a horizontal part of the organ case or frame, and A' the front board or stop-jamb through which the several stop-rods 1 2 3 4 work.

B is the main wind-trunk, situated vertically 65 at the end of the instrument, and extending horizontally from this from end to end are the several wind-chests C C' C'', &c., these being placed one above the other, as is usual in this class of organs, it being understood that the 70 reeds are arranged in the same horizontal plane in connection therewith.

For the sake of clearness I will describe in detail only one stop and its connections; but may here state that there is one stop for each 75 wind-chest and its series of reeds.

Taking the stop marked 1 as controlling the uppermost wind-chest C, (shown in Fig. 2,) to the inner end of the stop-rod is pivoted a connecting-rod D, preferably bifurcated at its 80 outer end, so as to embrace the bent arm e of a crank-rod or "roller" E, which is journaled horizontally upon the board A in bearings a a at each end, so as to be turned laterally therein by the movement of the stop-rod 1. 85 At or near the other end of this crank-rod E is another bent arm e', which, when the crank e assumes its vertical position, as seen in Fig. 2, impinges against and forces up one end of a spring valve-lever F, hung at f from the bottom of a valve-chamber G, thus depressing its other end, upon which is a proper disk f', and opening a port g previously covered by said disk. This port extends completely through the bottom of the valve-chamber G, its upper 95 end being controlled by a flat spring-valve G', contained within the chamber G, from the face of which depends a wire or spindle g', passing down through the port g, being just long enough to project below the mouth of 100 said port, where it is surmounted by a button g'', as shown in Fig. 9. When the parts are in this position, the inner valve G' is kept closed by its spring G'' and the lower valve is kept

open, as described. When the stop-rod 1 is not drawn out, the crank-arm *e'* is out of connection with the valve-lever *F*, and this lower valve is kept closed by the spring *F'*, (which 5 is stronger than the spring *G²*,) and the disk *f'*, pressing up against the button of the wire *g'*, forces the valve *G'* up and away from its seat, and thus throws the port *g* into communication with the valve-chamber *G*, this being 10 its normal position, as indicated in Fig. 10.

Intersecting the port *g* is a passage *h*, preferably made in the bottom board of the valve-chamber, and this is in communication with a conductor or pipe *H*, preferably extending 15 up through the wind-trunk *B* and forming junction with a block *k*, perforated internally, so as to communicate with a small "bellows-pallet" *K*, carried thereby. This block *k* being affixed to the division-board between the wind- 20 trunk and wind-chest *C*, the loose board of the pallet is adapted to cover the communicating orifice *c* by which the wind passes from the former to the latter. In pallets of this kind the leather is generally left somewhat loose 25 at the hinge-joint *k'*, and the moving board is consequently liable to sag, and thus improperly cover the opening *c*. Therefore I attach one end of a spring *L* to the edge of the moving board and the other to the pallet-block *k*, 30 which serves the double purpose of bracing up the hinge-joint and assisting to keep such moving board closed, it being remembered that the air-pressure from both sides is about evenly balanced. When the stop-rod is pushed 35 in, the valve *F* is closed and the valve *G'* open, and the valve-chamber *G* being always in communication with the wind-trunk *B* by means of the orifices *bb*, (shown in Fig. 8,) consequently the wind is filling the conductor *H* and pallet 40 *K*, inflating the latter and causing it to stop the orifice *c* and cut off that particular wind-chest. Upon the pulling out of the stop-rod, the closing of the valve *G'*, and opening of

valve *F*, in the manner already explained, the wind is shut off, and that heretofore inflating the bellows-pallet passes out through the open port *g*, the pallet being forcibly collapsed by the compressed air contained in the wind-trunk and the wind admitted from the trunk *B* to the wind-chest desired through the orifice *c*. 45 50

What I claim, and desire to secure by Letters Patent, is as follows:

1. The combination, with the stops, the wind-trunk *B*, and wind-chests *C*, of the valve-chamber *G*, having a series of valves *G'* therein, said chamber being common to all the valves and having a bottom board formed with a series of passages *h* and a series of ports *g* extending transversely thereof, the conducting-pipes *H*, leading from the passages *h* and extending through the wind-chest *B*, the valves *F* below the valve-chamber, and the collapsible pallets *K*, substantially as described. 55 60

2. The combination, with the stops, the wind-trunk *B*, and the chests *C*, of the valve-chamber *G*, having a series of stem-valves *G'* and having passages *h* communicating therewith through transverse ports *g*, the pivoted levers *F*, carrying the valves *f'*, and the crank-rod *e*, 70 connected to the stop for operating said lever. 65

3. The combination, with the valve-chamber *G*, having port *g*, of the valve *G²*, located within said chamber and having rod or wire *g'* projecting through said port, and the external spring valve-lever *F*, adapted to engage with said rod or wire, substantially in the manner and for the purpose specified. 75

4. The combination, with the collapsible pallet and block carrying same, of the spring 80 *L*, for the purpose described.

Toronto, 12th day of February, 1889.
CHARLES SUMNER WARREN.
